Primary Examiner — T. Chase Nelson(74) *Attorney, Agent, or Firm* — Banner & Witcoff, Ltd.(57) **CLAIM**

The ornamental design for a shoe outsole, as shown and described.

DESCRIPTION

FIG. 1 is a front perspective view of a shoe outsole showing my new design;

FIG. 2 is a plan view thereof;

FIG. 3 is a rear perspective view thereof; and,

FIG. 4 is an enlarged front perspective view thereof, wherein the unclaimed remainder of the shoe is omitted.

The broken lines showing the remainder of the shoe are for environmental purposes only and form no part of the claimed design.
